CERAMIC STILT FOR KILNS

Louis San Antonio, 96 Commodore St.,
Providence, R.I. 02904

Filed July 12, 1971, Ser. No. 161,399

Term of patent 14 years

Int. Cl. D23—99; D26—01
U.S. Cl. D23—82

FIG. 1

FIG. 2

FIG. 3

FIG. 4

FIG. 1 is a perspective view of a ceramic stilt for kilns embodying my new design;

FIG. 2 is a top plan view thereof;

FIG. 3 is a bottom plan view thereof; and

FIG. 4 is an edge view thereof.

The pins are shown in broken lines in FIG. 1 for illustrative purposes only.

I claim:

The ornamental design for a ceramic stilt for kilns, as shown and described.
